UNITED STATES PATENT OFFICE.

MAURICE HOUDAILLE, OF LEVALLOIS-PERRET, FRANCE.

GAS-DISCHARGING VALVE FOR HYDRAULIC APPARATUS.

1,402,610.

Specification of Letters Patent.

Patented Jan. 3, 1922.

Application filed June 23, 1919. Serial No. 306,180.

To all whom it may concern:

Be it known that I, MAURICE HOUDAILLE, a citizen of the French Republic, residing at 50 Rue Raspail, Levallois-Perret, Seine, France, have invented certain new and useful Improvements in Gas-Discharging Valves for Hydraulic Apparatus, of which the following is a specification.

This invention consists in improvements 10 in air-discharging valves fitted to hydraulic apparatus (such as for instance brake apparatus) in which use is made of the displacements of a movable member working in a liquid.

15 In such apparatus, it is known that in order to have a perfect operation, it is necessary that the casing in which the movable member (piston, vane, etc.) works, shall always be full of the incompressible liquid.

20 Moreover, it is necessary that no air shall be capable of entering the liquid since it would produce an emulsion that would change the characteristic features of the apparatus and its operation. Hence the necessity 25 of providing on the operative casing a supplementary filling reservoir which, through a suitable closing device, allows in one direction, of the inflow of incompressible liquid in order to keep the pump casing 30 filled, and allows in the other direction of the discharge of air which may have entered the apparatus.

The valve devices hitherto employed have not proved satisfactory. As a matter of fact 35 it is necessary that those valves shall be perfectly airtight since they must prevent all return of the liquid from the operating casing into the vessel designed to receive the liquid for keeping the casing filled. Since 40 expulsion of the air can take place only when by reason of the displacement of the movable member, the incompressible liquid has a tendency to flow back into the filling reservoir, it will be understood that there is 45 an incompatibility between the functions of the closing device which should at one and the same time be closed to prevent all movement of the liquid, and be opened to allow the passage of the air that is to be discharged from the operating casing.

50 The closing device forming the subject matter of this invention is designed to obviate the drawbacks above mentioned. It provides a closing device which at one and 55 the same time prevents all movement of the

liquid and allows the air to escape. It consists essentially in forming in the seat of the closing device, ducts which when the closing device is in its closing position, will allow the operative casing to communicate with the filling reservoir or with the atmosphere. By this means all movement of the liquid is prevented, while the air forced out by the movable member, finds an issue through the ducts provided in the seat of the closing device. A judicious selection of the dimensions of these ducts will allow, by reason of the viscosity of the liquid, of preventing any movement of the liquid through the said ducts, whereas air which is an elastic fluid, is able to pass freely through said ducts when the movable member is working in such a manner as to force back the liquid and effect a closing of the closing device.

The present invention is more particularly 75 adaptable for use in liquid shock-absorbers of the kind described in the U. S. Patent No. 1,087,017, dated February 10th, 1914.

This particular application of the present invention is illustrated by way of example 80 in the accompanying drawings in which:

Fig. 1 is a cross section of a liquid shock-absorber.

Fig. 2 is a vertical section on the line 2—2 of Fig. 1.

Fig. 3 is a separate section of the cover in which the air escape valve is located.

Fig. 4 is a front view of the said cover.

The shock-absorber comprises a cylindrical box *a* constituting the working chamber *b* of the braking members of the shock-absorber. This chamber is closed by a cover *c* screwed upon the cylindrical box *a* and prolonged by an internally screw-threaded tubular part *c'* into which is screwed a gland *d*. The spindle *e* extends through the gland *d*, and the braking vanes *f*, *f'* which it carries, move angularly in the working chamber *b* which is divided into two equal parts by fixed partitions *b'*, *b''* (Fig. 2).

A second convex cover *g* screwed on the periphery of the box *a* and traversed likewise centrally by the spindle *e*, constitutes the filling reservoir.

The end of the spindle *e* is made square to 105 carry the lever *h* which is held in place by a nut *i*.

When the lever *h* is rocked, it causes through the medium of the spindle *e*, the vanes *f*, *f'* working in their respective com- 110

partments, to move away from one of the fixed partitions, and consequently to move towards the opposite partitions.

This rotational motion of the vanes has the result of creating a vacuum in that part of the compartments that is comprised between the vanes and the fixed partitions from which they are moved away, and the liquid contained in the filling reservoir is drawn in passing, through a ball valve *j* located in the lower part of the cover *c*. During the period of compression of the liquid the air contained in the said liquid or contained in the working chamber *b* is forced into a passage *k* formed in the upper part of the cover *c* on the same vertical axis as the admission valve *j*, and closed by a ball valve *l*. Two saw cuts *m* (Figs. 3 and 4) made in the seat of the valve *l*, constitute ducts whose section is sufficient to allow of a free passage of the air which is thus discharged from the working chamber *b* with the same velocity as the liquid enters through the lower valve, this velocity being too low to allow the liquid to pass which is held back by the valve *l* bearing upon its seat.

From the foregoing it is to be understood that the operation of the valve is not altered, and that the opening and closing movements take place as usual, because the ducts formed by the saw cuts allow only the air to escape, which escape takes place at the same rate as the working chamber *b* is being filled, while preventing the passage of the braking liquid during the compression periods.

Consequently during the working of the shock-absorber there is a constant equilibrium between the inflow of the liquid and the outflow of the air, thereby avoiding a useless compression of the air which would merely lengthen the time taken in completely filling the working chamber.

The improved apparatus may be employed in cases where the working chamber is not surmounted by a filling reservoir as hereinbefore described. In such cases, the valve, arranged as described, would allow of a gradual escape of the air entering the apparatus during the filling which would otherwise form air pockets considerably modifying the characteristics and the working of the apparatus.

What I claim is:—

1. In a valve apparatus for discharging air or gases, adapted for use with hydraulic

apparatus in which use is made of the displacements of a movable member working in a liquid contained in a casing, the combination, with said casing, of a valve, a valve seat for the latter, and means whereby when said valve is seated upon its seat so as to close the aperture against the flow of the liquid that it controls, said valve will allow the escape of any air or gases that may have entered the said casing.

2. In a valve apparatus for discharging air or gases, adapted for use with hydraulic apparatus in which use is made of the displacements of a movable member working in a liquid contained in a casing, the combination, with said casing, of a valve, a valve seat for the latter, and ducts in said valve seat whereby when said valve is seated upon its seat so as to close the aperture against the flow of liquid, said ducts establish a constant communication between the outside and the inside of said casing, whereby any air or gas contained in said casing, but not the displaced liquid, can pass out through said ducts.

3. In a valve apparatus for discharging air or gases, adapted for use with hydraulic apparatus in which use is made of the displacements of a movable member working in a liquid contained in a casing, the combination, with said casing, of a valve, a valve seat for the latter, and saw cuts in said valve seat whereby when said valve is seated upon its seat so as to close the aperture against the flow of liquid, said saw cuts establish a constant communication between the outside and the inside of said casing, whereby any air or gas contained in said casing, but not the displaced liquid, can pass out through said sawcuts.

4. In hydraulic shock-absorbers, a casing and a reservoir, a partition separating said casing from said reservoir, and a valve mounted in said partition and permitting liquid to flow from the reservoir to the interior of the casing but preventing the flow of liquid from the casing to the reservoir, said valve at all times permitting the escape of air from the casing into said reservoir.

5. An apparatus of the kind defined by claim 4 in which the valve consists of a seat provided with saw cuts, and a ball engaging said seat.

In testimony whereof I have affixed my signature.

MAURICE HOUDAILLE,
